SPOOL CLAMP

Max Kiessling, Waterbury, Conn.

Application July 3, 1939, Serial No. 282,746

2 Claims. (Cl. 206—53)

This invention relates to clamps, and more particularly to a device adapted to be detachably secured to one flange of a spool or reel upon which is wound a coil of flexible material, such as a ribbon, cord or wire, and when in such position, to be operable to adjustably clamp the free end of said coiled ribbon, cord or wire to prevent it from unwinding from said spool or reel.

This invention is especially adapted to be used in place of pins, which were formerly employed, to attach the free end of a roll of ribbon to the body thereof without injuring the underlying layers of said ribbon.

The improved clamp may also be used for holding the free end of a roll of tape, film, wire, thread or other flexible member wound upon a spool or reel.

One object of this invention is to provide an improved clip-like device adapted to be detachably clamped frictionally to one side flange of a spool or reel, and having transverse means overlying the material wound thereon to adjustably clamp the free end thereof and prevent it from unwinding therefrom.

A further object of this invention is to provide an improved ribbon clamp of the above nature which will be relatively inexpensive to manufacture, simple in construction, compact, ornamental in appearance, and very efficient and durable in use.

With these and other objects in view, which will appear as the description proceeds, there have been illustrated in the accompanying drawing, two forms in which the invention may be conveniently embodied in practice.

In the drawing:

Fig. 1 is a perspective view of a spool of ribbon having one form of ribbon clamping device as it appears in operative position attached to a flanged spool.

Fig. 2 is a transverse cross-sectional view of the same.

Fig. 3 is a broken sectional view taken on the line 3—3 of Fig. 2.

Fig. 4 is an enlarged side view of the first form of ribbon clamp embodying the features and principles of this invention.

Fig. 5 is an enlarged front view of the same.

Fig. 6 is a broken front view of a ribbon spool having a modified second form of clamp applied thereto.

Fig. 7 is a side view of the modified form of ribbon clamp.

Fig. 8 is a front view of the same.

Referring now to the drawing wherein like reference numerals designate like parts throughout the several views, the numeral 10 denotes a spool, or reel, having a cylindrical, central hub portion 11 and a pair of flat annular side flanges 12 and 13 at each end of the portion 11. The spool is shown with a roll 14 of ribbon or tape wound upon its central hub portion 11 between the flanges 12 and 13, the outer free end of the ribbon 14 being indicated by the numeral 15.

The clamping means for adjustably holding the free end 15 to the roll of ribbon 14 is shown in Figs. 1 to 5 inclusive, as comprising a length of wire 16 bent into the form of an outer flat spiral coil 17, herein shown as having about one and three quarters turns, and provided with a straight intermediate portion 18 extending a short distance away from the spiral coil 17 in the plane thereof, and then having an inner straight transverse end portion 19 bent at right-angles to the plane of the spiral coil 17 and lying parallel to the layers of said ribbon. An arcuate substantially rectangular plate 20 curved to substantially conform to the cylindrical surface of the roll of ribbon 14 is hingedly secured to the wire end portion 19 by means of a pair of apertured ears 21 and 22 struck up from said plate and surrounding the straight end portion 19 of said wire clamp.

In the modified form of the invention shown in Figs. 6 to 8 inclusive, the transverse inner wire end portion 23 is much shorter in length than the corresponding transverse end portion 19 of the first described form, and no arcuate plate 20 is provided. In all other respects the two forms are the same.

Operation

In use, the flat spirally coiled portion 17 of both forms of the invention will first be frictionally clipped over one of the side flanges 12 or 13 in such a manner that the inner full-turn 24 of said coil 17 will lie outside the exterior surface 25 of the respective flange, and the outer substantially half-turn portion 26 will lie between the inside surface 27 of the respective flange and the roll 14 of ribbon wound on the hub 11. By means of this arrangement, the straight end portion 18 of the wire clamp will also lie between the flange and the roll of ribbon 14. The transverse wire end portion 19 and the arcuate plate 20 will rest upon the outer surface of the free end 15 of the ribbon, as shown in Figs. 1 to 3 inclusive, and adjustably hold it thereon.

In the modified form shown in Fig. 6, the short transverse wire end portion 23 rests directly upon the free end 15 of the ribbon and clamps it securely against the roll 14.

After the desired length of ribbon 14 has been unwound and severed from the roll 14 on the spool 10, the spiral coil 17 will be frictionally clipped over one of the flanges 12 or 13 and pressed inwardly as far as it will go. The arcuate plate 20 of the first form or the bare short transverse end portion 23 of the modified form will then be manually pressed against the newly cut free end 15 of the ribbon until the desired compression is obtained.

While there have been disclosed in this specification two forms in which the invention may be embodied, it is to be understood that these forms are shown for the purpose of illustration only, and that the invention is not to be limited to the specific disclosures, but may be modified and embodied in various other forms without departing from its spirit. In short, the invention includes all the modifications and embodiments coming within the scope of the following claims.

Having thus fully described the invention, what is claimed as new and for which it is desired to obtain Letters Patent, is:

1. In a device for clamping the free end of a ribbon wound upon a spool having spaced flanges

to hold said ribbon against the remaining underlying layers thereof, a flat spiral coil of wire frictionally clamped to one flange of said spool with the smallest convolution thereof disposed

5 outside of said flange and the largest convolution inside said flange, an intermediate straight section integral with and connected to the outer convolution of said coil and lying in the plane thereof, and a transverse portion bent at right-
10 angles to the plane of said flat coil and integrally connected to said intermediate section, said device being adapted to be secured upon said spool with said straight section lying within said flange and said transverse wire portion overlying said
15 ribbon and adjustably pressing inwardly against it.

2. In a device for clamping the free end of an elongated flexible member wound upon a flanged spool, a flat spiral coil of wire frictionally embracing one flange of said spool between the turns thereof, said wire coil having an intermediate straight section tangent thereto and lying in the plane thereof, a transverse inner end portion connected to said intermediate section and bent
20 at right-angles to the said plane, and an arcuate plate pivotally secured to said transverse end portion to adjustably press upon the free end of
25 said flexible member.

MAX KISSLING.
